ROOM THERMOSTAT

Jean Y. Barbier, St. Louis, Mo., assignor to International Oil Burner Company, St. Louis, Mo., a corporation of Missouri

Filed Dec. 20, 1965, Ser. No. 248

Term of patent 14 years

(Cl. D52—7)

FIG.1

FIG.2

FIG. 1 is a perspective view, partly from above and the right, of a room thermostat embodying my present invention. A view partly from the left would be a mirror image of that shown.

FIG. 2 is a bottom view thereof.

The rear side, not shown, is unornamented.

The surface shading on the front face of the thermostat, shown in FIGURE 1, is intended to represent fabric.

I claim:

The ornamental design for a room thermostat, substantially as shown and described.
